UNITED STATES PATENT OFFICE.

JAMES JOHN FLETT, OF CORVALLIS, OREGON.

PERFORATING-MACHINE.

SPECIFICATION forming part of Letters Patent No. 620,436, dated February 28, 1899.

Application filed March 8, 1898. Serial No. 673,072. (No model.)

To all whom it may concern:

Be it known that I, JAMES JOHN FLETT, of Corvallis, in the county of Benton and State of Oregon, have invented a new and Improved 5 Perforating-Machine, of which the following is a full, clear, and exact description.

The object of the invention is to provide a new and improved perforating-machine arranged to properly perforate a large number of sheets of paper, leather, wood, iron, or other material in such a manner that the perforations extend very close to each other and in perfect alinement to permit of readily detaching the sections of each sheet, as in blank-books, check, order, note, and other books, &c., the machine being simple and durable in construction, not liable to get out of order, and very effective in operation.

The invention consists of novel features 20 and parts and combinations of the same, as will be described hereinafter and then pointed out in the claims.

Reference is to be had to the accompanying drawings, forming a part of this specification, 25 in which similar characters of reference indicate corresponding parts in all the figures.

Figure 1 is a side elevation of the improvement. Fig. 2 is an enlarged transverse section of part of the improvement on the line 30 2 2 of Fig. 1. Fig. 3 is a sectional front elevation of the same on the line 3 3 of Fig. 2. Fig. 4 is a sectional plan view of the improvement on the line 4 4 of Fig. 1, and Fig. 5 is a transverse section of the same on the line 35 5 5 of Fig. 1.

The improved perforating-machine is provided with a table A, on which the material to be perforated is placed. The table A carries an overhanging arm B, provided at its 40 front with vertically-disposed guideways B', in which is fitted to slide a slide C, formed with a removable front portion C' and provided with a series of bearings for vertically-disposed drills D, extending with their lower 45 pointed ends a suitable distance below the bottom of the slide C, as is plainly indicated in the drawings. The drills D are arranged in perfect alinement with each other and very close to one another, as plainly indicated in 50 Fig. 3, and each drill is provided at or near its upper portion with a crank-arm D', engaging a bearing in a connecting-rod E, so that

when the latter is moved the several drills D are rotated in unison for perforating the material held below the drills on the table A. 55

The ends of the connecting-rod E are engaged by crank-arms F', arranged on the lower ends of shafts F, moving up and down with the slide C and having their upper ends mounted to turn with and slide in bevel-pin- 60 ions G, mounted to rotate in suitable bearings on the overhanging arm B. The pinions G are in mesh with bevel gear-wheels G', secured on a longitudinally-extending shaft G², mounted to rotate in suitable bearings on the 65 arm B and provided at one end with a crank-arm G³ or other means for imparting a rotary motion to the said shaft. Now when the shaft is rotated the gear-wheels G' rotate the pinions G and the said pinions ro- 70 tate the shafts F, so that the crank-arms F' impart a swinging motion to the connecting-rod E to simultaneously rotate the drills D.

The slide C is provided with an upwardly-extending link C², pivotally connected with a 75 lever C³, fulcrumed on the arm B and under the control of the operator, so that the lever C³ when swung causes the link C² to move the slide C and with it the drills D and shafts F to move in a like direction to feed the drills 80 through the material while the drills are rotated. A presser-foot H is fitted to slide in suitable bearings C⁴, arranged on the cover C' for the slide C, and the said presser-foot H has its lower end formed with bearings H' 85 for guiding the lower ends of the drills D. The presser-foot H is adapted to rest on the top of the material during the drilling operation, and when the drills are withdrawn after the perforation is completed by the operator 90 moving the lever C³ upward then the presser-foot will remain in contact with the uppermost sheet of the perforated material to permit a ready withdrawal of the drills without causing the material to move up through the 95 drills. The presser-foot H is pressed on by a spring H², coiled on a rod H³, carried by the cover C', and the upper end of the said spring rests on a nut H⁴, carried by the rod, while the lower end of the spring abuts against a 100 projection H⁵ on the presser-foot H. (See Fig. 5.) Thus the presser-foot is yieldingly mounted on the slide C.

In order to securely hold the material in

place on the table A during the perforating operation, I provide a clamping-bar I, extending in the rear of the drills to engage the top of the material and press the same firmly in 5 place against the table. For this purpose the clamping-bar I is mounted to slide vertically in bearings B², formed on the rear portion of the arm B, and the upper end of said bar is provided with a nut I', in which screws 10 a screw-rod J, mounted to turn in a suitable bearing B³, formed on the arm B, (see Fig. 5,) and on the upper end of the said screw-rod is a handle J' for turning the screw-rod and moving the bar I downward in firm contact 15 with the material, so as to clamp the same in place on the table.

The operation is as follows: The clamping-bar I and the slide C are held in an uppermost position to permit of placing the material in proper position on the table A, the line for the intended perforations being directly under the lower ends of the drills D. The operator now screws the screw-rod J down and moves the bar I in firm contact with the 25 material to clamp the same in place on the table, and then the operator turns the crank-arm G³ and simultaneously presses down on the lever C³ to cause a revolving of the drills D and a downward feeding of the same to 30 move the drills in contact with the material and bore holes therein, and thus form the perforations. When the material has been bored through, the operator ceases turning the crank-arm G³, then moves the lever C³ 35 upward to withdraw the drills from the material, and then the clamping-bar I is moved upward to release the material, which can now be removed.

Having thus fully described my invention, 40 I claim as new and desire to secure by Letters Patent—

1. The combination of the drills having crank-arms and axially-aligned portions at the opposite ends of each crank-arm, spaced bearings in which said axially-aligned portions are 45 journaled, and a driving mechanism engaging the crank-arms between the said bearings, substantially as described.

2. A perforating-machine, provided with a 50 slide, a plurality of drills journaled in the slide and movable therewith, and means, likewise carried by the slide to move therewith for rotating the drills, substantially as described.

55 3. A perforating-machine, comprising a stationary frame, a slide mounted to move thereon, drills journaled in the slide to move therewith, and driving mechanism comprising a portion carried by the slide and operating

the drills, and another portion carried by 60 the frame and having a sliding yet operative connection with the first-named portion of the driving mechanism, substantially as described.

4. A perforating-machine, comprising a stationary frame, a slide mounted to move thereon, drills journaled in the slide, means for operating the drills, and a presser-foot slidable on said slide, substantially as described. 65

5. A perforating-machine, provided with a 70 movable slide, a plurality of drills journaled in the slide and having crank-arms, a connecting-rod for the said crank-arms, and means carried by the slide and movable therewith for imparting motion to the crank-arms, 75 to rotate the drills in unison, substantially as shown and described.

6. A perforating-machine, provided with a movable slide, a plurality of drills journaled in the slide, and having crank-arms, a connecting-rod for the said crank-arms, means 80 carried by the slide and movable therewith for imparting motion to the crank-arms, to rotate the drills in unison, and a spring-pressed presser-foot fitted to slide on said 85 slide and having bearings for the lower ends of the drills, substantially as shown and described.

7. A perforating-machine, comprising a table having an overhanging arm, a clamping- 90 bar fitted to slide on said arm, and adapted to clamp the material to be perforated in place on the said table, a slide vertically adjustable on said arm, a plurality of drills journaled on 95 said slide and having crank-arms, a connecting-rod for the said crank-arms, and means for imparting motion to the said connecting-rod, to rotate the drills in unison, substantially as shown and described. 100

8. A perforating-machine, comprising a table having an overhanging arm, a clamping-bar fitted to slide on said arm, and adapted to clamp the material to be perforated in place on the said table, a slide vertically adjustable on said arm, a plurality of drills journaled on 105 said slide and having crank-arms, a connecting-rod for the said crank-arms, means for imparting motion to the said connecting-rod, to rotate the drills in unison, and a spring-pressed presser-foot fitted to slide on the said 110 slide and having bearings for the lower ends of the drills, substantially as shown and described.
